Assistant Examiner — Rodolfo Castro, Jr.

(57) **CLAIM**

The ornamental design for a protective case with multi-angle support, as shown and described.

DESCRIPTION

FIG. 1 is a perspective view of a protective case with multi-angle support showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the protective case with multi-angle support where the multi-angle support is configured in a first support angle;

FIG. 10 is a perspective view of the protective case with multi-angle support where the multi-angle support is configured in a second support angle;

FIG. 11 is a perspective view of the protective case with multi-angle support where the multi-angle support is configured in a third support angle;

FIG. 12 is another perspective view of FIG. 9;

FIG. 13 is another perspective view of FIG. 10; and,

FIG. 14 is another perspective view of FIG. 11.

The broken lines in the drawings depict portions of the protective case with multi-angle support that form no part of the claimed design.

1 Claim, 14 Drawing Sheets
